UNITED STATES PATENT OFFICE

HARLOWE HARDINGE, OF YORK, PENNSYLVANIA, ASSIGNOR TO HARDINGE COMPANY, INCORPORATED, OF YORK, PENNSYLVANIA, A CORPORATION OF NEW YORK

GRINDING MILL

Application filed August 30, 1929. Serial No. 389,339.

This invention relates to grinding mills, and more particularly to means for controlling the operating characteristics of a grinding mill having inlet and outlet openings at one end for permitting elastic fluid to enter and leave the mill. 55

Among the objects of the invention is to provide means whereby currents of air or of other elastic fluid introduced into a grinding mill may be varied in their course within the mill to suit existing grinding conditions and to enable the production of a uniform product of a desired fineness. 60

Another object of the invention is to provide means for enabling regulation of the fineness and quantity of ground material removed from a grinding mill by fluid flotation. 65

Other objects and advantages of the invention will be pointed out hereinafter in the description and claims and illustrated in the drawings, in which: 70

Fig. 1 is a section of a conical mill diagrammatically illustrating effects produced by means of the present invention. 75

Fig. 1A is a detail illustrating how the conical deflecting means may be constructed in sections. 80

Fig. 2 is a cross sectional detail of conical deflecting means adapted to replace similar means illustrated in Fig. 1. 85

Fig. 3 is a sectional elevation of the discharge end of a grinding mill in association with exhaust means. 90

Fig. 4 is a detail taken on line 4—4 of Fig. 3. 95

Although the invention has application to other forms of grinding mills, it is particularly suited for use in connection with the well known Hardinge conical mill in connection with which I have chosen to illustrate the principles thereof. One form of the conical mill is illustrated in Fig. 1. The drum has a cylindrical portion 10 and conical end portions 11, 12 which are secured to trunnions 13, 14, respectively. Material is fed from the hopper 15 at the feed end of the mill through trunnion 13. As illustrated, the mill may be closed by a plate 16 at the feed end of the mill and the air currents which are used to carry the product from the mill are caused to enter 100 at the discharge end of the mill through

trunnion 14 and to leave the mill through a conduit 17, centrally disposed within trunnion 14. Plate 16 is essential when the mill is to be operated under pressures other than atmospheric pressure. 55

When the conical mill is used with its fluid inlet and outlet openings at one end it operates on a reverse current principle, the fluid currents entering through annular opening 18 and leaving through conduit 17. Conduit 17 is supported within trunnion 14 by means of stays 19 which are spaced peripherally about conduit 17 so as to permit air to freely pass through the space 18. The reverse current principle by which the ground product of a mill is removed has been very satisfactory in the past, and the substance of the present invention is directed to the production of a uniformly fine product of a desired fineness. Such refinement of operating characteristics is a feature particularly desired in mills which are used in installations in which coal is ground and directly fed to the furnaces. Without the improvements to be described hereinafter, it has been found that the fluid currents passing through a mill are likely to occasionally pick up particles of material larger than of the size desired as a product. For grinding ordinary materials such as clay and ores, this result offers no particular problem because it is possible to provide a classifier adapted to return the oversize material to the drum for re-grinding, but when the grinding mill is used in an installation for grinding coal it is desirable that no oversize material be permitted to be carried to the burners, and that the use of special classifiers be eliminated because of the high velocity of the air passing through and leaving the grinding mill. 90

In order to control the action of air currents entering the mill I provide a deflecting surface in the form of a conical member 21, Fig. 1, which may be made up of several parts or of integral construction. This member is spaced from the wall of the drum by means of webs 22 which extend radially therefrom and are associated with a lining member 23. When the conical deflecting means 21 is made up of several members, 100

each individual member may take the form of that illustrated in Fig. 1A, in which 21a is a portion of the conical deflecting means, 23a is a lining member and 22a is a web connecting the portion of the deflector means 21a with the lining member 23a. The deflecting means is provided to deflect air entering the mill in a course along the inner wall of the drum so that the wall of the drum will be swept by a fast moving current of air.

During the rotation of any mill a certain portion of the product or material inside of the mill sticks or adheres close to the lining. 15 This action may be reduced by providing smooth linings, but it is desirable that linings be ribbed or grooved in order to prevent material within the mill from sliding as the drum rotates, and unless some provision is 20 made for releasing the fine material adhering close to the lining such material will not be available as a product and will also adversely affect grinding conditions. When a grinding mill is in operation, the material 25 adhering to the linings drops across the current of air and is sucked out of the system. Some of this material has not been sufficiently ground to the desired fineness and it would not be removed from the mill but for 30 the fact that it is caused to fall across the path of a current of air leaving the mill. In accordance with the principles of my invention, any material clinging to the lining will drop as usual, but it will first come into 35 contact with the current of air entering the mill and be carried by that air in a course along the inner wall of the mill. This current of air blows the material back into the mill before it may reach the discharge current of air going in the other direction. 40 This action is produced by the deflecting qualities of the conical deflecting means 21 which is so positioned in the inlet portion of the mill to direct the incoming currents of air. As illustrated in Fig. 1, a particle of 45 material reaching the position as at 25 would be carried by the incoming current of air in a direction similar to that described by the broken line 26 and would follow a trajectory carrying the particle well backward into the mill. The velocity of the air in the vicinity of 25 is much higher than when the particle reaches a remote portion of its trajectory for in the latter position the mill is 50 of greater volume and the velocity of the air is reduced and, therefore, the particle is permitted to fall without coming into contact with the high velocity air about to leave the mill through conduit 17.

55 The air stream developed by the conical deflecting means 21 will tend to push the grinding media and material back into the mill. This result is diagrammatically illustrated by the curve 27 identifying the lay of material within the mill under certain oper-

ating conditions. When the velocity of the air in the mill is high, the material will take a position somewhat similar to that shown by the line 27 and when the velocity of the air is of less intensity the material will take a position somewhat similar to that shown by the broken line 28. It is, therefore, apparent that a much higher load can be carried within the mill without fear of discharging the product by gravity for the air following a course as at 29 will prevent discharge of product by gravity through the space 18 and will also keep the material well out of reach of the outlet conduit 17.

60 The use of a conical deflecting surface similar to that shown at 21 improves the operating characteristics of a conical grinding mill and enables a greater degree of fineness of product to be produced as well as permits the use of greater velocity for the 65 air. This is due in part to the action of the incoming air in keeping the material away from the discharge end of the mill and in part upon the high velocity of the air stream along the inner wall of the mill. Accordingly, oversize particles are blown away from the outlet conduit 17 and only the very fine particles which are picked up by air in reversing its direction will go out through the outlet conduit 17. Within certain limits 95 the higher the velocity in the mill the finer will be the product.

It is apparent that under certain conditions it might be desirable to vary the space between the conical deflecting surface and the wall of the mill in order to enable a change in the velocity of the air passing through this space to be made without resort to a change in the speed of the exhauster. In Fig. 2 I have illustrated a deflecting conical surface 121 which is connected to a lining member 123 by means of a plurality of webs 122. The space between the conical surface 121 and lining member 123 is less than the space between conical surface 21 and lining member 23 illustrated in Fig. 1. In order to make corresponding members interchangeable it is only necessary that lining member 123 be similar in size and be similarly holed as lining member 23.

105 As illustrated in Fig. 3, it is also possible to vary the space between the conical deflecting surface and the wall of the mill by mounting a conical member 32 so that it may be adjustably positioned along outlet conduit 33. The large end of the member 32 is provided with a disk 34 riveted thereto and having a flange 35 engaged by bolts 36. These bolts fit into slots 37 which are sufficiently long to permit the maximum amount 110 of adjustability of member 32 longitudinally of outlet conduit 33.

115 In Fig. 3 there is also shown means for controlling the quantity of material removed from the grinding mill. Outlet conduit 33 120

opens into a box 39 which is in communication with the chamber 40 of an exhauster 41. Box 39 has an opening 42 for receiving air from conduit 33 and opening 43 for receiving air from an air supply conduit 44. Air supply conduit 44 is connected with the air inlet opening 45 of the grinding mill 46. 47 is an adjustable damper or closure whereby it is possible to vary the area of openings 42 and 43. The single damper may be operated by sprocket 48 having engagement with a rod 49 to which the damper 41 is attached. The relation of closure 47 to openings 42 and 43 is such that as one of these openings is being closed the other opening is being increased in area and vice versa. As illustrated in Fig. 3, damper 47 is in a mid-position and each of openings 42, 43 has approximately one-half of its area obstructed. 20 In this position some of the air drawn through air supply conduit 44 will by-pass the mill and be drawn through opening 43 into box 39 while the quantity of air permitted to flow from the mill through outlet 33 is restricted. When closure 47 is in its lowermost position, conduit 33 will be entirely closed and all the air flowing through conduit 44 will be by-passed through opening 43 into box 39. In its highest position closure 47 will entirely close opening 43 and all of the air drawn through air supply conduit 44 will pass through the mill and be taken therefrom through outlet conduit 33.

Hopper 50 provides means by which may be removed tramp oversize material which may come out of the grinding mill during overloading conditions. As illustrated in Fig. 4, wings 51, 52 are provided for enabling adjustment of the size of the opening 43.

Adjustable damper 47 makes it possible to make a very positive and quick control of the output of the grinding mill and it also makes it possible to maintain a relatively high velocity of air through the mill to keep conditions in the mill substantially the same under all loads. Furthermore, in systems in which the grinding mill is not sealed at its feeder end, it is possible to balance the pressures within the mill by the proper adjustment and use of damper 47.

What is claimed is:

1. In a grinding mill, the combination with a rotary drum having an inlet opening and having an outlet opening at one end thereof, said inlet opening surrounding said outlet opening, of deflecting means in said inlet opening deflecting fluid currents along the wall of said drum.

2. The combination set forth in claim 1 in which provision is made for permitting changes in the area between the deflecting means and the drum.

3. In a grinding mill, the combination with a rotary drum having a conical discharge por-

tion with an outlet opening and an inlet opening at the small end of the conical discharge portion, said inlet opening surrounding said outlet opening, of conical deflecting means in said inlet opening whereby elastic fluid entering the drum is caused to be directed along the inner surface of the drum. 70

4. The combination set forth in claim 3 in which means are provided for permitting adjustment of the position of the conical deflecting means relative to the drum. 75

5. In a grinding mill, the combination with a rotary drum having a conical discharge portion with an outlet opening and an inlet opening, said outlet opening comprising a conduit extending through the discharge end of the drum and said inlet opening comprising the space between the outlet conduit and the drum, of a conical deflecting surface disposed in the space between the outlet conduit and the drum but permitting elastic fluid entering the drum to pass between it and the drum. 80 85

6. In a grinding mill, the combination with a rotary drum having a conical discharge portion with an outlet opening and an inlet opening, said outlet opening comprising a conduit extending through the discharge end of the drum and said inlet opening comprising the space between the outlet conduit and the drum, of exhauster means having connection with said outlet conduit for causing fluid currents to pass into and out of said drum, and means including a conical deflecting surface in the inlet opening and an adjustable damper for the outlet opening for regulating the fineness and quantity of ground material removed from the drum by fluid flotation. 90 95 100

7. In a grinding mill, the combination with a rotary drum having an inlet opening and having an outlet opening at one end thereof, said inlet opening surrounding said outlet opening, of a conduit supplying fluid current to said inlet opening, means for drawing fluid through said conduit and from said drum through said outlet opening, and adjustable means controlling the quantity of fluid drawn from said drum through said outlet opening. 105 110

8. The combination set forth in claim 7 in which the adjustable means controls the size of an opening connecting the fluid supply conduit with the means for drawing fluid from the drum. 115

9. In combination, a grinding mill having outlet and inlet openings at one end, means closing the other end of the mill against the passage of fluid currents, blower means for causing fluid currents to pass into and out of the mill through said inlet and outlet openings, and means for simultaneously regulating the flow of the elastic fluid into the mill and the discharge of material-laden fluid from the mill. 120 125

10. In combination, a grinding mill having outlet and inlet openings at one end, means 130

closing the other end of the mill against the passage of fluid currents, means for causing fluid to enter into said inlet conduit and to leave the mill through said outlet conduit, and an adjustable regulating damper for controlling the amount of fluid current entering and leaving said mill, said regulating damper being operative to regulate the size of an opening through which some of the fluid current may be by-passed through the blower means without entering the mill.

11. In combination, a grinding mill having outlet and inlet openings at one end, means closing the other end of the mill against the passage of fluid currents, and deflector means deflecting fluid currents entering the mill away from the outlet opening out of the mill.

12. In combination, a rotary grinding mill having outlet and inlet openings at one end, stationary inlet and outlet ducts having connection with said inlet and outlet openings, blower means for causing the flow of elastic fluid through said ducts, a duct chamber disposed at the end of said mill and having connection with said ducts and with said blower means, means for regulating the flow of elastic fluid through said ducts, said means comprising a by-pass between the duct delivering elastic fluid to said mill and the duct chamber, and a damper variably positionable for controlling the amount of elastic fluid flowing from said mill to said duct chamber and for concomitantly controlling the opening of said by-pass.

13. The combination set forth in claim 12 in which said last named means and damper are manually controlled.

14. In combination, a rotary grinding mill having outlet and inlet openings at one end, means in said mill for deflecting the elastic fluid current entering the mill away from the elastic fluid current leaving the mill, stationary inlet and outlet ducts having connection with said inlet and outlet openings, means for causing the flow of elastic fluid through said ducts and mill, a duct chamber disposed at the end of said mill and having connection with said ducts and with said first-named means, a by-pass between the duct delivering elastic fluid to said mill and the duct chamber, and a damper variably positionable for controlling the amount of elastic fluid flowing from said mill to said duct chamber and for concomitantly controlling the opening of said by-pass.

15. In combination, a grinding mill comprising a rotary drum having a grinding compartment comprising a conical feed end and a conical discharge end, said discharge end having outlet and inlet openings, ducts having connection with said inlet and outlet openings for introducing elastic fluid to said mill and for removing elastic fluid from said mill, one of said ducts being disposed within the other of said ducts, exhaust means for

causing movement of elastic fluid through said ducts, and deflector means for deflecting fluid currents entering the mill through said inlet opening away from said outlet opening.

In testimony whereof I hereto affix my signature.
